COMPRESSOR CYLINDER HEAD ASSEMBLY

William F. Borgerd, Evansville, Ind., assignor to
International Harvester Company, a corpora-
tion of New Jersey

Application May 26, 1949, Serial No. 95,425

7 Claims. (Cl. 230—230)

1

This invention relates to compressors used in refrigerators and the like, and more particularly to valve structures for the intake of gas into a compressor cylinder and the discharge of compressed gas therefrom.

In conventional compressors which employ reciprocating pistons expanded gas is drawn from the crank case of the compressor to the cylinder where the gas is compressed and then discharged. Inasmuch as the crank case is generally filled with lubricating oil the gas frequently carries a slug of oil with it to the cylinder. This is undesirable since the oil, being of greater density than the gas, will be hampered in its passage from the cylinder, causing abnormal stresses and strains on the valve parts. Hence, it is one of the objects of this invention to provide a discharge valve structure capable of accommodating slugs of oil.

The volumetric efficiency of small compressors used in refrigerators is notoriously poor. The volume of refrigerant gas actually pumped is usually considerably less than the swept volume of the pistons. One of the chief factors directly influencing the volumetric efficiency is the clearance volume. Theoretically, an ideal compressor would not have cylinder clearance volume. However, because of structural necessities, the ideal compressor is not obtainable. Thus, it is another important object of this invention to provide a valve structure for a compressor which utilizes a small volume to operate efficiently and quietly with a resultant smaller cylinder clearance volume.

Another object of this invention is the provision of a novel valve plate which is easily adjustable to allow a variation in clearance volume and that is thin yet strong so that the volume represented by the discharge holes through this plate is at the very minimum.

A still further object is the provision of a cylinder head which dissipates heat generated within the cylinder in such a manner that the temperature will be maintained within safe working limits without the utilization of separate power consuming cooling means.

Still another object is the provision of a novel supporting structure for the valve plate.

Another object is the provision of novel guide means for the discharge valve ring.

A still further object is to provide a cylinder head spacer which prevents gas leakage from the cylinder and also provides a novel seating means for the inlet valve ring.

The foregoing and other important objects and desirable features inherent in and encompassed by the invention together with many of the purposes and uses thereof will become readily apparent from a reading of the ensuing description in conjunction with the annexed drawings.

Fig. 1 is a plan view showing a portion of the compressor in section.

2

Fig. 2 is a view similar to Fig. 1, but showing the discharge valve ring in its discharge position.

Fig. 3 is an enlarged detail view showing the cylinder head spacer.

5 Referring to the drawings in which like characters designate like elements in the various views, a compressor cylinder head assembly is shown which includes a cylinder block 10 having a counterbored portion 11 to form an internal 10 annual shoulder or bearing surface 12 and a longitudinally extending portion 13.

A cylinder 14 is disposed within the cylinder block 10 and is concentric with the cylinder block counterbored portion 11. A piston (not shown) is adapted to reciprocate within the cylinder 14. The cylinder 14 has a plurality of circumferentially spaced radially extending inlet ports 15 located approximately midway between its longitudinally spaced ends. Apertures or ports 15 are provided to insure an adequate volume of refrigerant gas within the cylinder 14 on the compression stroke of the piston. A flange 16 projects radially outwardly to provide a portion 17 to bear on annular shoulder or bearing surface 12. It will be noted that cylinder 14 is stiff enough to be supported at one end only. Radially inwardly of the portion 17, the flange 16 has a portion 18 provided with a plurality of circumferentially spaced substantially longitudinally extending apertures or inlet openings 19. Apertures 19 form inlet passages or openings to the cylinder 14 from the space 20 located between the interior surface 21 of the cylinder block 10 and the outer surface 22 of the cylinder 14. Space 20 communicates with ports 15 and the crankcase (not shown).

Positioned within the counterbored portion 11 on flange 16 and having its outer peripheral surface 23 abutting the internal surface of the longitudinally extending portion 13 is a ring-like 40 cylinder head spacer 24. Referring to Fig. 3, two surfaces 25 and 26 each have a continuous small bead of lead alloy (or other soft metal) 27 fused thereon to function as a seal preventing gas leakage from the cylinder 14. The spacer 24 has a radially inwardly projecting tapered flange portion 28, the lower surface 29 of which is inclined upwardly and inwardly as viewed in Figs. 1 and 3 for a purpose which will be explained hereinafter.

50 A thin, circular flexible valve ring 30 concentric with cylinder 14 is positioned between the lower surface 29 of flange portion 28 and flange 16. In one position, during the compression stroke of the piston, the valve ring 30 covers apertures or openings 19 in flange portion 18. It is to be understood that valve ring 30 takes the form of a flat ring when no external forces are acting upon it. The outer periphery 31 of valve ring 30 is enclosed in an annular groove 32 formed by a portion 33 of lower surface 29 and the cylinder flange 16. Referring to Fig. 3, the

detail view of the spacer 24, it will be noted that the annular surface 34 has a longitudinal dimension just long enough to give ample space for valve ring 30 to be lightly held on its outer periphery. On the intake stroke of the piston a vacuum is developed within the cylinder which causes valve ring 30 to "dish" upwardly to uncover openings 19. Thus, the inner annular edge 35 tends to twist or move longitudinally upwardly as viewed in Fig. 1 since the outer edge or periphery 31 is confined in the annular groove 32. The valve ring 30 tends to "undish" and close openings 19 when the vacuum within the cylinder 14 is removed. Lower surface 29 is inclined upwardly and inwardly to provide ample clearance for the inner annular edge 35 to flex longitudinally to uncover openings 19 and allow a flow of refrigerant gas through them. It will be noted that the lift or longitudinal movement of the inner annular edge 35 is restrained to a very small amount to insure the least possible volume in the inlet valve pocket 36. Thus, inlet ports 15, as stated above, are provided near the bottom of the piston stroke to insure complete filling of the cylinder 14 even though some small flow restriction is experienced through openings 19. It will be apparent that with this inlet valve construction a very economical and quiet operating structure is provided.

Positioned over the spacer 24 and being adapted to about the same is a circular valve plate 37. Valve plate 37 has a plurality of circumferentially spaced discharge openings 38 therethrough to allow compressed gas to be discharged from the cylinder 14. Valve plate 37 is relatively thin as compared to conventional valve plates in similar compressors where the thickness varies from $\frac{3}{8}$ " to $\frac{1}{2}$ " thick. Obviously the difference in thickness between the present valve plate and the prior conventional plates represents clearance volume saved. Furthermore, the resistance to gas flow through the discharge openings 38 is reduced considerably by making the valve plate comparatively thin.

Longitudinally spaced from the valve plate is a cylinder head 39 having a surface 40 rounded or contoured to conform to the internal wall 41 of the cylinder compressor housing 42 partially shown in Fig. 1. The cylinder head 39 abuts the wall 41 to save space and to obtain the best possible heat dissipation of the compressed gases. With this head construction the heat has a direct metal to metal flow to the external surroundings of the compressor without the need of a power consuming cooling system. The head 39 has a centrally located downwardly depending boss 42' projecting inwardly toward the cylinder 14 and a plurality of circumferentially spaced bolt receiving holes 43. Means are provided for clamping the cylinder 14 on the internal annular shoulder 12 of the cylinder block 10 which include a plurality of threaded bolts 44 extending through holes 43 and aligned apertures 45 in the valve plate 37 to engage threaded openings 46 in the cylinder block 10. It will be noted that cylinder 14 may be easily assembled or disassembled with this type of clamping means.

The valve plate 37 is supported by a threaded member 47 projecting longitudinally from the boss 42'. One end of threaded member 47 is rigidly secured to a central portion 48 of the valve plate 37 by any known manner such as riveting. The other end of member 47 is received in a threaded aperture 49 in the boss 42'. As stated previously, the valve plate 37 is relatively thin

and therefore the greatest deformation of the plate 37 would occur at its center when under the influence of a force acting on one side or the other. Thus it will be apparent that by supporting the valve plate 37 at its center a structurally strong device is provided which will withstand the action of the variable cylinder pressure on one side and the compressed gas pressure on the other side. It will also be noted that the heat developed within the cylinder may be conducted from the supporting means, to the cylinder head, to the housing, and then to the external surroundings.

When assembling the valve plate 37 to the cylinder head 39 any desired degree of center tightening can be obtained since the valve plate 37 can be rotated as little as a quarter turn when approaching the final position if four bolts 43 are used. The valve plate 37 can thus be adjusted or deformed to give a little more or a little less "dish" so that its clearance from the piston top in its top dead center position can be made very small.

A discharge valve ring 50 concentric with and encircling the valve plate supporting structure is positioned over the discharge openings 38 to cover them. The valve ring 50 is capable of moving longitudinally but is restrained from moving transversely by four or more feet 51 extending from reinforcing ribs 52 in the cylinder head and a valve guide 51. The valve guide 51 is a circular plate concentric with and secured to the supporting member 47. Its radially disposed outwardly facing peripheral surface 52 acts as a sliding surface for the inner edge of the valve ring 50. A helical spring 53 abuts the valve ring 50 and the underside of cylinder head 39 to urge said valve ring 50 on the valve plate 37 to a valve closed position.

A resilient stop means is provided to permit a maximum amount of area for the passage of an oil slug if such should be discharged from the cylinder. In normal operation of the compressor the refrigerant enters through inlet ports 15 and openings 19 during the suction stroke of the piston after which it is compressed and forced through discharge openings 38 to a discharge pipe (not shown). In compressing the refrigerant and forcing it through the discharge openings 38, the valve ring 50, which is normally positioned as shown in Fig. 1, and which is maintained in such position by the helical spring 53 until sufficient pressure is exerted against the spring 53, is moved longitudinally upwardly as viewed in Fig. 1 to uncover openings 38, permitting a flow of refrigerant therethrough. The longitudinal movement of valve ring 50 is limited by a buffer plate 54 longitudinally spaced from the valve plate 37 and supported on the valve guide 51. The buffer plate 54 has a radially projecting portion 55 overhanging the peripheral surface 52 of the valve guide 51 which contacts the valve ring 50 and prevents further longitudinal movement of said valve ring 50 away from the valve plate 37. Buffer plate 54 is slidably mounted on supporting member 47. A star or leaf spring 56 abuts the underside of boss 42' and buffer plate 54 to urge the buffer plate 54 on the valve guide 51. The spring 56 has a greater compressive strength than the helical spring 53 and will normally maintain the buffer plate 54 immovable. However, should a slug of lubricating oil be discharged through the openings 38 the valve ring 50 is permitted to abut the projecting portion 55 of the buffer plate 54 and move it

longitudinally compressing star spring 56 to provide a large discharge area for the passage of the slug.

It will be apparent from the foregoing description that a valve structure mounted in a cylinder head assembly has been provided which is particularly advantageous for use in refrigerator compressors since it is more efficient in operation and considerably quieter than valves in known compressors.

The embodiment of the invention chosen for the purposes of illustration and description herein is that preferred, keeping in mind the requirements for achieving the objects of the invention and developing the utility thereof in a most desirable manner, due regard being had to existing factors of economy, simplicity of design and construction, production methods and the improvements to be effected. It will be appreciated, therefore, that the particular structural and functional aspects emphasized herein are not intended to exclude, but rather to suggest, such other advantages and modifications of the invention as fall within the spirit and scope of the invention as defined in the appended claims.

What is claimed is:

1. In a compressor, the combination comprising a cylindrical housing; a cylinder block counterbored at one end to form an internal annular shoulder and a longitudinally extending portion; a cylinder concentric with said counterbore having a plurality of circumferentially spaced, radially extending apertures between its longitudinally spaced ends, said cylinder having a radially projecting flange at one end, said flange having a portion adapted to bear on said annular shoulder and a second portion radially inwardly of said bearing portion provided with a plurality of circumferentially spaced, substantially longitudinally extending apertures; a ring-like spacer positioned on said flange having its outer peripheral surface abutting the interior surface of said longitudinally extending portion, said spacer having a lower surface inclined upwardly and inwardly; a circular valve ring concentric with said cylinder and positioned between said lower surface and said flange being adapted to close said longitudinally extending apertures in one position, said valve ring having its outer periphery enclosed in an annular groove formed by a portion of said lower surface and said flange whereby said valve ring is capable of twisting about its outer periphery to a second position wherein said apertures are open; a cylinder head having a surface contoured to conform to the interior wall of said housing and being adapted to abut the same, said head having a centrally located boss projecting inwardly toward said cylinder; a valve plate being adapted to abut said spacer and having a plurality of circumferentially spaced openings; means to clamp said cylinder on said internal annular shoulder including a plurality of threaded bolts extending through aligned openings in said head and valve plate to engage threaded bolt receiving apertures in said cylinder block; valve plate supporting means comprising a threaded member secured to a central portion of said valve plate and held in a threaded aperture in said boss; a discharge valve ring concentric with said supporting means, said discharge valve ring being positioned over said valve plate openings and being adapted to move longitudinally away from said valve plate; a

first spring abutting said head and said discharge valve ring to urge said ring on said valve plate, said spring being helically wound and of greater diameter than said boss; a discharge valve ring guide concentric with and secured to said supporting means and having its radially disposed outwardly facing peripheral surface adapted to provide a sliding surface for said discharge valve ring; and resilient stop means to limit the longitudinal movement of said discharge valve ring, said means comprising a buffer plate longitudinally spaced from said valve plate and supported on and concentric with said valve guide, said buffer plate having a radially extending portion overhanging the outer peripheral surface of said valve guide and being adapted to slide longitudinally on said supporting means for said valve plate, a second spring of greater compressive strength than said first spring abutting said boss and said buffer plate to urge said buffer plate on said valve guide.

2. In a compressor, the combination comprising a cylindrical housing; a cylinder block having a counterbored portion at one end to form a bearing surface; a cylinder disposed within said block having a radially projecting annular flange at one end, said flange having a portion adapted to be supported on said bearing surface and having a plurality of circumferentially spaced inlet openings inwardly of said bearing surface; a spacer comprising a ring having an outside diameter substantially equal to the inside diameter of said counterbore, said spacer being adapted to bear on said flange and be positioned within said counterbore, said spacer having a radially inwardly projecting tapered flange portion; an inlet valve ring positioned between said tapered flange portion and said flange on said cylinder being adapted to close said inlet openings; a cylinder head having a surface contoured to conform to the interior wall of said housing and being adapted to abut the same, said head having a centrally located boss projecting inwardly toward said cylinder; a valve plate being adapted to abut said spacer and having a plurality of circumferentially spaced discharge openings; means to clamp said cylinder on said counterbored portion including a plurality of threaded bolts extending through aligned openings in said head and valve plate to engage threaded bolt receiving apertures in said cylinder block; valve plate supporting means comprising a threaded member secured to a central portion of said valve plate and held in a threaded aperture in said boss; a discharge valve ring concentric with said supporting means, said valve ring being positioned over said discharge openings and being adapted to move longitudinally away from said valve plate; a first spring abutting said head and said discharge valve ring to urge said ring on said valve plate, said spring being helically wound and of greater diameter than said boss; a valve ring guide concentric with and secured to said supporting means and having its radially disposed outwardly facing peripheral surface adapted to provide a sliding surface for said valve ring; and resilient stop means to limit the longitudinal movement of said discharge valve ring, said means comprising a buffer plate longitudinally spaced from said valve plate and supported on and concentric with said valve guide, said buffer plate having a radially extending portion overhanging the outer peripheral surface of said valve guide and being adapted to slide longitudinally on said supporting means for said valve plate, a second spring of greater compressive strength than said first spring abutting said boss and said buffer plate to urge said buffer plate on said valve guide.

second spring of greater compressive strength than said first spring abutting said boss and said buffer plate to urge said buffer plate on said valve guide.

3. In a compressor, the combination comprising a housing; a cylinder block having an internal annular shoulder at one end; a cylinder having a radially projecting annular flange to abut said annular shoulder, said flange having a plurality of inlet openings therethrough; a spacer positioned on said flange and being provided with a radially inwardly projecting portion, said portion having its lower surface inclined upwardly and inwardly; an inlet valve ring positioned between said lower surface and said annular flange being adapted to close said inlet openings in one position and to open said inlet openings in another position; a valve plate adapted to abut said spacer and having a plurality of circumferentially spaced discharge openings; a cylinder head having a surface contoured to conform to the interior wall of said housing and being adapted to abut the same; means to clamp said cylinder on said annular shoulder; adjustable valve plate supporting means including a centrally located downwardly projecting portion of said cylinder head adapted to be secured to a central portion of said valve plate; a discharge valve ring concentric with said supporting means, said discharge valve ring being adapted to move longitudinally away from a first valve closed position to a second valve open position; resilient stop means to limit the longitudinal movement of said discharge valve ring, said means comprising a buffer plate longitudinally spaced from said valve plate having a portion adapted to abut said discharge valve ring in its second valve open position, a spring urging said buffer plate in the direction of said valve plate; and resilient means urging said discharge valve ring on said valve plate, said resilient means having a smaller compressive strength than said resilient stop means.

4. In a valve structure, the combination comprising a cylinder head having a central portion projecting therefrom; a valve plate longitudinally spaced from said head, said plate having a plurality of circumferentially spaced discharge openings therein; adjustable supporting means for said plate including a supporting member projecting from said central portion and secured to said valve plate; a discharge valve ring concentric with said valve plate and being adapted to cover said discharge openings, said valve ring being adapted to move longitudinally from a valve closed position to a valve open position; a valve guide for preventing transverse movement of said valve ring, said guide comprising a circular plate concentric with and secured to said supporting member and having its radially disposed outwardly facing peripheral surface adapted to provide a sliding surface for said valve ring; a helical spring normally urging said valve ring to said valve closed position; a buffer plate longitudinally spaced from said valve plate and supported on and concentric with said valve guide, said buffer plate having a radially projecting portion overhanging said peripheral surface of said valve guide and being adapted to move longitudinally on said supporting member; and a second spring of greater compressive strength than said helical spring abutting said central portion of said cylinder head and said buffer plate to urge said buffer plate on said valve guide.

5. A valve structure including a valve plate having a plurality of circumferentially spaced openings therein; a valve ring positioned over

7
8
said openings for closing said openings, said ring being adapted for longitudinal movement; a cylinder head longitudinally spaced from said plate having a boss projecting toward said valve plate; supporting means for said plate including a member projecting from said boss and secured to a central portion of said plate; a valve ring guide positioned between said boss and said plate, said guide being secured to said supporting means; 10 a spring associated with said valve ring continually urging said ring on said plate; a resilient stop means limiting the longitudinal movement of said valve ring, said means including a disc-like member positioned between said boss and valve ring guide and slidably mounted on said supporting means, and a spring tending to urge said disc-like member on said guide.

6. In a valve structure, the combination including a cylinder block counterbored at one end to form an internal annular shoulder and a longitudinally extending portion; a cylinder concentric with said counterbore having a plurality of circumferentially spaced, radially extending apertures between its longitudinally spaced ends, 20 said cylinder having a radially projecting flange at one end, said flange having a portion adapted to bear on said annular shoulder and a second portion radially inwardly of said bearing portion provided with a plurality of circumferentially spaced, 25 substantially longitudinally extending apertures; a ring-like spacer positioned on said flange having its outer peripheral surface abutting the interior surface of said longitudinally extending portion, said spacer having a lower surface inclined upwardly and inwardly; a circular valve ring concentric with said cylinder and positioned between said lower surface and said flange adapted to close said longitudinally extending 30 apertures in one position, said valve ring having its outer periphery enclosed in an annular groove formed by a portion of said lower surface and said flange whereby said valve ring is capable of twisting about its outer periphery to a second position wherein said apertures are open.

40 7. In a valve structure, the combination including a cylinder having a radially projecting flange at one end, said flange having a plurality of circumferentially spaced apertures; a circular valve ring concentric with said cylinder and positioned over said apertures; a ring-like spacer positioned on said flange having a radially inwardly projecting portion, said portion having a lower surface inclined upwardly and inwardly; a valve ring concentric with said cylinder and positioned between said lower surface and said flange adapted to close said apertures in one 45 position, said valve ring having its outer periphery enclosed in an annular groove formed by a portion of said lower surface and said flange whereby said valve ring is capable of twisting about its outer periphery to a second position wherein said apertures are open.
